(57) **CLAIM**

The ornamental design for a power scrubber, as shown and described.

DESCRIPTION

FIG. 1 is a front perspective view of a power scrubber, showing our new design in an extended position;

FIG. 2 is a front view thereof;

FIG. 3 is a rear view thereof;

FIG. 4 is a left side view thereof;

FIG. 5 is a right side view thereof;

FIG. 6 is its enlarged top plan view;

FIG. 7 is its enlarged bottom plan view;

FIG. 8 is a front perspective view, shown in a contracted position;

FIG. 9 is a front perspective view, shown in an alternate position;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1; and,

FIG. 14 is an enlarged detail view of area 14 in FIG. 9.

The broken lines in the drawings illustrate the portions of the power scrubber, which form no part of the claimed design.

(Continued)

The long-dash-dot-short-dash broken lines encircling the enlarged views are for depicting enlarged view indicators and form no part of the claim thereof.
